UNITED STATES PATENT OFFICE

EDGAR B. NICHOLS, OF CAMDEN, NEW JERSEY, ASSIGNOR TO THE PFAUDLER CO., OF ROCHESTER, NEW YORK, A CORPORATION OF NEW YORK

LIQUID-PROCESSING APPARATUS

Original application filed January 27, 1928, Serial No. 250,048. Divided and this application filed December 22, 1928. Serial No. 328,032.

The present invention relates to a liquid processing apparatus of the heat exchange type and has for its object to provide improved means of this class designed particularly for use in the treating of liquids, such for example, as are employed in the processing of foods and other substances by heating or cooling treatment.

A further object of the invention is to provide an improved heat exchange system embodying a container for the fluid to be treated or processed having therein conducting means for a heating or cooling medium designed in such manner as to permit the heating or cooling surface to be increased or decreased as desired in accordance with the quantity or nature of the liquid to be processed.

A further object of the invention is to provide an improved arrangement of heating or cooling coils or sections designed for conveniently regulating the extent of the effective surface of the coils by individual control thereover and also control by pressure responsive devices whereby to more effectively and economically treat the liquids.

A further object of the invention is to provide an improved arrangement of heating or cooling coils designed in a manner to permit additional coils to be readily added or replacements made from time to time with but little inconvenience.

To these and other ends the invention resides in certain improvements and combinations of parts, all as will be hereinafter more fully described, the novel features being pointed out in the claims at the end of the specification.

In the drawings:

Fig. 1 is a part sectional elevation of an apparatus embodying the present invention;

Fig. 2 is a sectional plan of the same;

Fig. 3 is a fragmentary sectional elevation taken on line 3^a—3^a of Fig. 2;

Fig. 4 is a fragmentary sectional plan taken on line 4^a—4^a of Fig. 3;

Fig. 5 is a fragmentary sectional plan taken on line 5^a—5^a of Fig. 3, and

Fig. 6 is a fragmentary sectional plan taken on line 6^a—6^a of Fig. 3.

Similar reference numerals throughout the several views indicate the same parts.

The present application is a division of my copending application, Serial Number 250,048, filed January 27, 1928, for improvements in liquid processing apparatus.

In the manufacturing or processing of food products, as for example, the pasteurizing of milk or the treating of other liquids, it is essential to have a series of conducting units for the heat exchange medium to be used designed so as to permit of the employment of varying quantities of the medium as may be required for different quantities of the liquids to be processed or treated from time to time. In other words, the area of the heating or cooling surface should be proportional to the quantity of liquid to be treated and in the present invention the coils have been so designed that they may be independently controlled for this purpose.

Furthermore, the coils at the points where they discharge into the outlet pressure head are provided with automatic pressure operated valves which open and close according to the variations in pressure on the opposite sides thereof, but which are arranged to prevent backflow of the steam or other medium from the head to the coils discharging thereto.

The coils are so constructed that they may be readily assembled within the tank by building up or superimposing one section upon another and the arrangement shown is such that the sections, in case of repairs, may be quickly removed with but little interruption in the use of the apparatus and with comparatively small expense.

In the present arrangement the several coil sections each has a separate inlet and a separate outlet, check valves being provided for each outlet as will be hereinafter explained. The passages through the individual sections are completely separated from each other between the base inlet and outlet heads upon which the sections are supported as shown in Fig. 3.

Referring to the drawings, the tank is shown at 46 and is provided at one side with a flanged head 47 having four inlet passages 61 to 64 inclusive with which are connected

four supply pipes 61^a to 64^a inclusive while a fifth pipe 76^a leads to a passage 76 of the head which discharges into the tubes of section 52 as shown in Fig. 5. The pipes are each provided with suitable valves not shown, for individually controlling the supply of steam or liquid to the several sections so that any one of the sections may be closed at will or the supply of fluid thereto regulated in accordance with varying requirements under different operating conditions. Four of the sections 48 to 51 inclusive, are superimposed upon the head 47 and the fifth or lowermost section 52 has its inlet end projecting laterally therefrom as shown in Fig. 1 and its outlet end leading into an oppositely positioned head 53 which has an extension 53^a from which leads downwardly a pipe 54 connecting with a head 55 secured on the bottom of the tank 46. The discharge pipe 56 leads from the head 55 preferably to a suitable container not shown for receiving the exhaust steam or other heating or cooling medium employed in the processing operations.

25 The inlet heads 48^a to 51^a inclusive of the sections 49 to 51 are provided at their lower sides with transversely extending plates or disks 57 to 60, which form removable bottoms for said heads adapted to close the 30 openings therein whereby to separate one head from another. The opposite heads 48^b to 51^b preferably have their lower walls cast integral with the heads as shown at the right of Fig. 3. The four passages 61 to 64 terminate 35 in vertically disposed outlet openings each of which, except the passage 64, is adapted to receive the lower end of a tube in the manner indicated in Fig. 3. Two of these tubes are shown at 65 and 66, the former extending 40 upwardly through the inlet heads of the sections and discharging into the head 48^a while the latter extends upwardly and discharges into head 49^a. The tube discharging into head 50^a is shown only at 67 in Fig. 45 4, but its construction is the same as that of the other tubes. The tubes may either be supported through engagement of their lower ends with the head 47 or they may have flanges at their upper ends as indicated in 50 Fig. 3 which overlie the uppermost plates through which the tubes extend and by which they may be supported. No tube is provided for opening 64 of head 47 since said opening discharges directly into head 51^a.

55 The outlet heads of the coil sections 48^b to 50^b are provided respectively with downwardly extending tubes 68, 69 and 70, the latter being shown only in Fig. 6. The lower ends of said tubes are seated upon and supported by the lower wall 71 of head 51^b over openings therein leading to the interior of head 53. The wall 71 is provided with an additional opening 72, Fig. 6, so that the steam or other fluid passing through section 65 51 may discharge directly into head 53. The

opening 72 and those beneath tubes 68, 69 and 70 are provided with check valves 73 slidable on studs 74 depending from wall 71 and carrying coil springs 75 for holding the valves seated as shown in Fig. 3 whereby to prevent discharge of the fluid upwardly from one coil to another should the pressure become greater on the lower faces of the valves than on the upper faces thereof. It will be seen, therefore, that should the pressure in head 53, produced by the fluid entering it from section 52, exceed the pressure in any one of the sections 48 to 51, the valves for said sections will be closed until the pressure in the latter builds up sufficiently to open the same. It will be understood that the valves operate independently of each other and therefore each section of the coil will be opened or closed by its valve according to the difference in pressure on the opposite sides of the valve. However, while the fluid is discharging from head 53 the pressure therein will become slightly lowered so that the greater pressure above the valves will open the same to afford proper circulation of the fluid through the individual sections of the coils. As stated above, however, the valves will prevent the upward discharge of the steam or other fluid from the lowermost head 53 to the heads thereabove should the pressure on the lower sides of the valves become greater than on the upper faces thereof.

The tubular sections 48 to 51 being inclined downwardly from their inlet to their outlet ends will insure proper drainage of the fluid 100 so that its accumulation within the sections is thus prevented.

I claim as my invention:

1. In a fluid circulating system, a plurality of tubular sections having connected inlet and outlet portions, individual fluid inlet and outlet members each extending through the walls of one of said sections and discharging into another section whereby the circulating passages of the sections are kept separate and independent of each other, and means for supplying fluid to said inlet members. 105 110

2. In a fluid pressure circulating system, a plurality of pipe sections having connected inlet and outlet portions, fluid inlet and outlet members extending within said portions arranged in a manner whereby the circulating passages of the sections are separate and independent of each other, a head connected with one of said outlet portions arranged to receive the fluid from said outlet members, and pressure responsive valves for checking the back flow of the fluid from the head through said outlet members. 115 120

3. In a fluid pressure circulating system, a plurality of superimposed pipe sections having outlet portions resting one upon another, separate supply pipes for said sections, a receiving head for the fluid circulated through said sections, tubes leading from the outlet 130 125

- portions of a plurality of the sections through the outlet portions of the remaining sections therebeneath to said head, and automatic valves for said tubes responsive to the difference in pressure within the tubes and the head.
4. In a fluid pressure circulating system, a plurality of superimposed pipe sections having inlet and outlet heads, individual supply tubes for the inlet heads each extending to one of the latter through the inlet head of another section, means for conveying fluid to the tubes, and means connecting said sections one with another.
- 10 5. In a fluid pressure circulating system, a plurality of superimposed pipe sections having inlet and outlet heads, individual supply tubes for the inlet heads each extending to one of the latter through the inlet head of another section, a receiving head for the fluid, separate discharge passages leading from the sections to said receiving head, means for conveying fluid to the tubes, and means connecting said sections one with another.
- 15 6. In a fluid circulating system, a plurality of superimposed coils, means for conveying the fluid to the coils, one or more discharge tubes each arranged to extend from one coil through a portion of another, and valves for checking the back flow of the fluid through the discharge tubes.
- 20 7. In a fluid circulating system, a plurality of pipe sections disposed one upon another and having alined outlet portions, means for conveying fluid to said pipe sections, and individual discharge tubes for each of a plurality of the sections extending transversely of said sections and each projecting through the walls of the outlet portions of one or more of the 25 remaining sections, said walls having fluid tight joints surrounding the tubes at the points through which they project.
- 25 8. In a fluid circulating system, a plurality of superimposed pipe sections, means for conveying fluid to said sections, a receiving head for the fluid circulated through said sections, and a vertically disposed discharge tube leading downwardly from one of the sections through the wall of another to said receiving head, said last mentioned section having a 30 separate discharge passage.
- 35 9. In a fluid circulating system, a plurality of connected pipe sections, means for conveying fluid to said sections, a receiving head for the fluid circulated through said sections, a discharge tube leading from one of the sections through a portion of another to said receiving head, and a pressure responsive spring pressed valve for the tube arranged 40 between the latter and the head adapted to close automatically when the pressure in the head exceeds the pressure in the pipe section with which the tube is connected.
- 45 10. In a fluid circulating system, a plurality of connected pipe sections provided with alined inlet and outlet heads resting one upon another, outlet tubes leading from a plurality of said heads each through one of the remaining outlet heads, inlet tubes for said sections, a receiving head for the fluid discharged by said outlet tubes, valves for checking the back flow of the fluid from the receiving head through said outlet tubes, and a supply head having separate passages for conveying the fluid to the inlet tubes.
- 50 11. In a fluid circulating system, a plurality of pipe sections extending alternately in opposite directions and having their ends provided with opposite sets of alined inlet and outlet heads having end walls seated one upon another, the circulating passages of said pipe sections being separate from and independent of each other, a separate supply conduit leading to each inlet head through one of its end walls, a separate discharge conduit leading from each outlet head through one of its end walls, and means serving to secure said sections one upon another.
- 55 12. In a fluid circulating pressure system, a plurality of pipe sections extending alternately in opposite directions and having their ends provided with opposite sets of alined inlet and outlet heads having end walls seated one upon another, the circulating passages of said pipe sections being separate from and independent of each other, a separate supply conduit leading to each inlet head through one of its end walls, a separate discharge conduit leading from each outlet head through one of its end walls, a receiving head connected with each discharge conduit, and valves for said discharge conduits arranged to be automatically closed when the pressure in said receiving head is greater than in the pipe sections with which said discharge conduits are connected, and means serving to secure said sections one upon another.
- 60 13. In a fluid circulating system, a plurality of pipe sections extending alternately in opposite directions and having their ends provided with opposite sets of alined inlet and outlet heads seated one upon another, the circulating passages of said pipe sections being separate from and independent of each other, a separate supply conduit leading to each inlet head, means for separately conveying the fluid from each outlet head, and means serving to secure said heads one upon another.
- 65 14. In a fluid circulating system, a plurality of pipe sections extending alternately in opposite directions and having their ends provided with opposite sets of alined inlet and outlet heads seated one upon another, a supply head seated upon one of said inlet heads, a receiving head seated upon one of said outlet heads, separate supply passages leading from the supply head to each of said inlet heads, separate outlet passages leading from each outlet head to said receiving head,

and means serving to secure said sections one upon another.

15. In a fluid circulating pressure system, a plurality of pipe sections extending alternately in opposite directions and having their ends provided with opposite sets of aligned inlet and outlet heads seated one upon another, a supply head seated upon one of said inlet heads, a receiving head seated upon one of said outlet heads, separate supply passages leading from the supply head to each of said inlet heads, separate outlet passages leading from each outlet head to said receiving head, valves for each of said outlet passages arranged to be automatically closed when the pressure in the receiving head is greater than in said sections, and means serving to secure said sections one upon another.

16. In a fluid circulating system, a plurality of pipe sections extending alternately in opposite directions and having their ends provided with opposite sets of aligned heads having transverse walls seated one upon another, separate inlet conduits leading to the heads of one set through said transverse walls, separate outlet conduits leading from the heads of the opposite set, means for conveying fluid to each of said inlet conduits, and means serving to secure said pipe sections one upon another.

17. In a fluid circulating system, a plurality of pipe sections extending alternately in opposite directions and having their ends provided with opposite sets of aligned heads having transverse walls seated one upon another, separate inlet conduits leading to the heads of one set through said walls, separate outlet conduits leading from the heads of the opposite set, means for conveying fluid to each of said inlet conduits, a receiving head connected with the outlet conduits, a discharge pipe leading from said receiving head, and means serving to secure said pipe sections one upon another.

45 18. In a fluid circulating system, a plurality of pipe sections extending alternately in opposite directions and having their ends provided with opposite sets of aligned heads having transverse walls seated one upon another, separate inlet conduits leading to the heads of one set through said walls, separate outlet conduits leading from the heads of the opposite set, means for conveying fluid to each of said inlet conduits, a receiving head connected with the outlet conduits, valves for said outlet conduits arranged to automatically close the latter when the pressure in the receiving head is greater than in the sections from which the outlet conduits lead, a discharge pipe leading from said receiving head, and means serving to secure said pipe sections one upon another.

19. In a fluid circulating pressure system, a plurality of pipe sections extending alternately in opposite directions and having their

ends provided with opposite sets of aligned heads having transverse walls seated one upon another, separate inlet conduits leading to the heads of one set through said walls, separate outlet conduits leading from the heads of the opposite set, a supply head having passages leading to the several inlet conduits, a receiving head into which the outlet conduits are arranged to discharge, valves for said outlet conduits arranged to be automatically closed when the pressure in the receiving head is greater than in the pipe sections from which the outlet conduits lead, said supply and receiving heads having seats engaging the heads of one of the pipe sections, and means serving to connect said pipe sections and said supply and receiving heads.

20. In a fluid circulating system, a plurality of pipe sections extending alternately in opposite directions and having their ends provided with opposite sets of aligned inlet and outlet heads, the heads of each set being disposed one upon another, separate supply and discharge conduits leading respectively to and from said inlet and outlet heads, a supply head engaging one of the inlet heads arranged to deliver fluid to each supply conduit, a receiving head connected with each of said outlet conduits and being disposed in engagement with one of the outlet heads, and a control valve for each of said discharge conduits arranged to automatically close the latter when the pressure therein is below that in the receiving head.

21. In a fluid circulating system, a plurality of pipe sections, one of which comprises a base section, said sections extending alternately in opposite directions and having their end portions arranged to form opposite sets of aligned inlet and outlet heads, a fluid supply head connected with the inlet head of said base section, a fluid receiving head connected with the outlet head of said base section, said last mentioned outlet head having independent discharge passages corresponding to each pipe section, all leading to said receiving head, a conduit leading from each outlet head opposite that of said base section arranged to discharge through one of said passages to said receiving head, a supply conduit for each inlet head connected with said base section, said supply conduits communicating each with said supply head, the latter having a passage leading directly to the inlet head of said base section, the outlet head of the base section having a discharge passage leading directly to the receiving head, and means serving to secure said pipe sections and said supply and receiving heads one upon another.

22. In a fluid circulating system, a plurality of tubular sections arranged one adjacent another and each having an inlet portion, and a plurality of fluid supply tubes for individually conveying fluid to the dif-

ferent sections, each extending through the walls of the inlet portion of one section and discharging to the inlet portion of another section.

5 23. In a fluid circulating system, a plurality of tubular sections arranged one adjacent another, and individual fluid inlet and outlet tubes for conveying fluid to and from said sections, each of the tubes extending through the walls of one section and discharging to another section.

10 24. In a fluid circulating system, a plurality of tubular sections arranged one adjacent another, individual outlet tubes for a plurality of the sections each connected with and extending from one section through the walls of another section and serving to convey fluid from the section with which it is connected through said walls, and valve means for controlling the passage of the fluid through said tubes.
